UNITED STATES PATENT OFFICE

2,610,362

ROTARY ROLL CLEAVER FOR DRAFT FRAMES

Whitworth F. Bird, Swarthmore, Pa., assignor to
 Collins & Aikman Corporation, Philadelphia,
 Pa., a corporation of Delaware

Application November 17, 1948, Serial No. 60,535

4 Claims. (Cl. 19—131)

1

This invention relates to draft frames for textile fibers. More particularly it is directed to a rotary clearer roll conveniently driven from a usual frame part. It may readily be applied to existing frames and is an inexpensive feature of new frames.

These improvements have application to those types of textile processing machinery in which wild fibers are given to licking around a roll, apron or the like and forming an undesirable lap. The formation of a lap will sometimes require stoppage of the entire frame and correction of the fault before processing can be continued. These improvements provide for positioning the clearer roll in contact with the roll to be cleared and a driving means to rotate it in a direction opposite to the roll or member it clears and at any desired rate.

It is believed that this characteristic of fibers to lap accounts, to a considerable extent, for certain design features of well known type frames; for example, the Bradford spinning frame often used on long wools and mohair usually has front rolls about 4" in diameter, whereas much of the equipment used for shorter fibers has front rolls in the range of 1" to 1½" in diameter.

It further appears to be widely recognized that fiber length and fineness are important in the selection of processing machinery. This is strikingly borne out by the processing of synthetic fibers as has been done for a great many years on practically all types of yarn preparing machinery, i. e. those sometimes referred to as worsted, woolen, cotton, flax and the like. Similarly A. F. Barker, for example, has as early as 1929, suggested in the Journal of Textile Science that wool might be clipped after about 2" growth and processed on so called cotton machinery. Additionally, within the systems, for example the worsted, French, Anglo Continental or Bradford and individual machines in each have all been recognized as having such application for drawing etc. within certain ranges of textile fiber length or condition such as combed or uncombed.

It will be appreciated then that in drafting equipment designed for universal use with respect to fibers of about 1" to approximately 12" in length or in equipment designed for drafting long fibers and where an attempt is made to control the fibers in the drafting area up to a point very close to the nip of the drawing off rolls, it is desirable to use relatively small front rolls of say 1" to 2" in diameter. As suggested above, excessive clapping will

sometimes occur in small roll machines processing long fibered stock. Clearer rolls or means are conventionally used to prevent lapping. Usually the clearer means are frictionally driven rolls or are fixed and do not rotate. Neither of these types is satisfactory for processing fibers like mohair which has a long average length or for processing certain blends having similar characteristics.

10 I have found that a draft frame roll such as a lower front roll when cooperating with a clearer roll operating in contact and in the opposite direction may, insofar as lapping is concerned, function very similar to a large roll and in some respects better, as when the clearer surface moves slightly slower than the roll surface. What laps as will occur are soft as there is no tendency to "draft," and the laps are readily removable. It is believed that both contact and reverse direction are essential to prevent fibers from passing between the rolls. Cutting of laps, if such be necessary, may readily be done forwardly of the nip with a hook knife.

25 According to these improvements I provide a clearer roll driven in a direction opposite to the direction of travel of the roll or apron which it clears. My clearer is easily removable although the need for removal is greatly lessened than in prior constructions of which I am aware.

30 Also my clearer roll may continuously or intermittently be in contact with the bottom roll by selection of proper configuration of the clearer surface. Thus an intermittent action may be simply produced with a continuous drive.

35 The drive belt may be an elastic or nonelastic band or chain looped and joined so as to pass around shafts or pulleys. When elastic, it may hold the clearer against the bottom roll or the bottom roll and apron requiring only a guide for installation. The elastic loop may be formed from rubber and the like or by a spring.

40 Alternatively, fixed rotatable means such as a pulley or the clearer itself may be rotated by a simple elastic or nonelastic driving belt. The clearer surface may be a brush, felt, flannel or plush having straight or inclined pile.

45 An object of my invention is to provide a clearer roll particularly adapted for installation and contact with a comparatively small front roll of draft frames.

50 Another object is to provide an improved clearer roll mechanism in which the clearer roll rotates in contact with but in the opposite direction to its companion roll or apron.

55 Another object is to provide a continuous or

intermittent clearer action in a reverse direction to the roll being cleared.

Another object is to provide an operating and clearer roll operating in contact so as to function similarly to a large roll with respect to the formation of laps.

Another object is to provide an efficient clearer action for small roll machines in which the fibers being processed may be controlled very close to the drawing off nip.

These and other objects will be manifest from a consideration of the following description, claims and drawings in which:

Fig. 1 is a somewhat diagrammatic, side elevation showing a roll stand of a single apron type frame and a belt type drive for a clearer roll in operating contact with a lower delivery roll of a draft frame.

Fig. 2 is a similar front view showing the readily removable clearer roll fixed in position and the aligned relationship of the driving elements.

Fig. 3 shows a polygon clearer roll which might be used in the combination.

Fig. 4 is a line elevation of a modification in which both the apron and a roll are cleared.

In Fig. 1 is shown a draft frame roll stand 20 having the usual front delivery rolls 10, 11, and pairs of feeding rolls 12, 13 and 14, 15. The bottom rolls are usually positively driven and the rolls 13 and 15 rotate at a substantially slower rate than the roll 11, as will be understood. The rolls are supported in adjustable stands 16 and 17.

Top rolls 12 and 14 may be moved with their companion rolls. The series of pairs of back rolls 14, 15 and 12, 13 provide for the ratch and fiber control. When fibers are longer than the circumference of roll 11, they have an unusually strong tendency to lap around this roll 11 and form a hard lap. Conventional clearers do not satisfactorily correct the difficulty.

The front roll 11 is supported in frame roll stand 20. These are conventionally spaced at four spindle intervals. The roll 11 is less than $2\frac{1}{2}$ " in diameter, preferably between $1\frac{1}{4}$ " and 2" even in frames capable of drafting strands containing fibers 8 or 10 inches in length.

A nose bar 18 is positioned close to the nip to support the apron 19, which is held under tension by weight 21 held in position at its stud shafts 22 by lever 23 pivoted on frame 20 at 24. Pencil or tumbler roll 25 may also be supported by the nose bar 18.

A clearer roll 26, having a continuous or intermittent pile surface 28, has a cross-like extension 30, which fits into a recessed portion 32 of channel pulley 34. This pulley 34 is preferably proportioned so as to rotate the clearer roll 26 somewhat slower than the frame roll.

The pulley 34 is fixed in the frame stand 20 by short shaft 36, the pulley being free to rotate. A similar channeled member 38 or recess 40 on the shaft 41 is aligned with 34. A round elastic or nonelastic closed loop member such as belt 42 connects the roll shaft 41 to the clearer roll pulley and rotates it. It is to be noted that while the clearer roll 26 rotates in the same direction as roll 11, its contacting side is moving in an opposite direction.

Fig. 2 shows a driving gear 44 for the bottom roll shaft and the belt arrangement. The other end of the clearer roll has a depressible support member 46 held outwardly by spring 48 in a manner known per se. This, of course, facilitates proper positioning of the clearer roll.

Fig. 3 shows a polygon clearer roll 50 and conventional supporting stud 54.

Fig. 4 is a modification in which an elastic or nonelastic belt drive may be used, the basic parts of the frame being the same and similarly numbered to the same parts in Fig. 1. A fixed plate 60, slotted as at 61, 62 to receive the clearer roll 70, has locking pins 63, 64. When the clearer 70 is in slot 62, it engages both the apron 19 and bottom roll 11. When in slot 61 only the bottom roll is cleared. This is the source of greater difficulty.

The clearer 70 has studs 72 which are guided in the slots 61 and 62. When the belt 65 is elastic, it will at once support the clearer roll 70 in contact with roll 11 and drive it in contact in the opposite direction. A taut belt will operate somewhat similarly, but presents maintenance difficulty in this structure or requires tensioning parts. The belt is preferably formed by looping and connecting the ends of a straight member, although chains and sprockets are deemed equivalent. The pins 63, 64 prevent the clearer from falling as the drive is usually from one end only.

The clearer roll could quite conceivably be driven from another of the usual driven shafts, as shafts 11, 13 and 15 all rotate in the same direction. Rolls 10, 12, 14 are more usually weight rolls not especially suited to use as a source of power. In structures where the top roll is driven, the belt would be crossed to form an 8 as a loop of the illustrated embodiments would not produce the essential result.

Having described my invention in connection with preferred embodiments and wishing not to be limited thereto but only by the scope of the following, I claim:

1. In a draft frame, feeding means, delivery means including a front delivery bottom roll, a driving and supporting shaft for the said bottom roll, a rotatable clearer roll, a supporting shaft for said clearer roll, guide means on the frame for receiving an end of the clearer roll supporting shaft and to aid in positioning the clearer roll in contact with the bottom delivery roll, locking means for holding the clearer roll shaft within said guide means, and means, including a closed loop, for connecting the bottom driving and supporting shaft and the rotatable clearer roll supporting shaft in driving relationship and for holding the clearer roll in contact with said bottom roll.

2. The invention of claim 1 further characterized by the fact that the clearer roll surface is polygonal and constructed and arranged so that its surface is periodically out of contact with said clearer roll thereby providing an intermittent clearing action.

3. In an apron type draft frame, an apron, apron tensioning means, feeding means, delivery means including a front delivery bottom roll, a driving and supporting shaft for the said bottom roll, a rotatable clearer roll, a supporting shaft for said clearer roll, guide means on the frame for receiving an end of the clearer roll supporting shaft in locking engagement in a plurality of positions and to aid in positioning the clearing roll in contact with said apron and with said bottom delivery roll or in the alternative, in contact with the bottom delivery roll only and drive means connecting the bottom roll shaft and the clearer roll shaft.

4. The invention of claim 3 further characterized by the fact that the means for receiving an end of the clearer roll supporting shaft con-

sists of a plate having a plurality of guide slots and locking means associated with said slots, and elastic drive means connecting the delivery roll and the clearer roll shafts, whereby said clearer roll shaft is retained in the selected guide slot.
